UNITED STATES PATENT OFFICE

2,423,662

PHONOGRAPH PICKUP DEVICE

Bruce Roberts, Philadelphia, Pa., assignor, by
mesne assignments, to Philco Corporation,
Philadelphia, Pa., a corporation of Pennsyl-
vania

Application September 8, 1944, Serial No. 553,156

1 Claim. (Cl. 179—100.41)

1

The present invention relates to a phonograph pick-up for utilization with frequency modulation radio receivers and particularly to a pick-up of the inductance type which has high sensitivity as compared with other pick-ups of the same general type.

It is an object of this invention to provide a device which will effect the foregoing by aiding rather than diminishing the flux lines and by concentrating these flux lines into narrower paths.

Further objects and features of my invention will be apparent when the following description is considered in connection with the annexed drawing in which:

Figure 1 is a longitudinal, vertical, cross-sectional view of the device of my invention; and

Figure 2 is a cross sectional view of the device taken upon the line 2—2 of Figure 1.

Both figures are on an enlarged scale.

Referring now to the drawing it will be seen that the device comprises a housing 10 formed of non-magnetic material, this housing being illustrated as being generally square in cross section although, of course, any other form desired may be utilized. Within the housing 10 there are two iron shells 11 and 12 which are made of high permeability powdered iron and comprise cuplike members having the upstanding pole pieces 13 and 14 at their centers. In the annular spaces formed between the exterior walls and the pole pieces 11 and 12 are two coils 15 and 16 which may be wound upon the spools 17 and 18 and thereafter slipped into place in the annular spaces mentioned or if desirable may be placed in the annular spaces without use of the spools.

A disk 20 of high permeability powdered iron and of substantially the same cross sectional dimension as the pole pieces 13 and 14 is located in the gap between the pole pieces, this disk being supported on the upper end of the lever 21, which lever is mounted, as, for example, by means of the pin 22, for movement across the pole pieces. Pin 22, as clearly indicated in Figure 1, is supported in the housing 10 and the lower end of lever 21 extends through a slot cut in the housing and terminates in a stylus 23 which is designed to cooperate with the grooves of the ordinary phonograph record.

Lever 21 is mounted rigidly on pin 22 so that

2

disk 20 is normally positioned with its center separated from the axis of the pole pieces 13 and 14, as shown in Figure 2. A torsional resilient force tending to hold lever 21 in this position is provided by pin 22, or by any other convenient spring means.

It will be seen that as the stylus moves in the grooves of the phonograph record the disk 20 moves to positions such that its axis is more or less nearly coincident with the axis of the pole pieces 13 and 14. By this means the reluctance of the magnetic circuit is changed and the magnetic flux about coils 15 and 16 is increased and decreased and the frequency of the associated resonant system correspondingly decreased and increased.

It will also be clear that the use of the high permeability iron disk tends to raise the overall Q of the resonant circuit of which the coil forms a part. It will also be seen that the introduction of the iron of disk 20 makes the lines of magnetic flux follow along the pole pieces and therefore requires a much smaller movement of the lever 21 and stylus 23 in order to produce a given change in the resonant frequency of the resonant circuit comprising the coil and its associated shunt condenser (not shown). A suitable oscillator circuit for use with the frequency modulation pick-up of the present invention is described in United States Patent No. 2,322,621, issued June 22, 1943.

While I have described a preferred embodiment of my invention it will be obvious that other embodiments and constructions may be adopted without departing from the spirit thereof and, consequently, I desire to be limited not by the foregoing description, but solely by the scope of the appended claim.

What is claimed is:

40. In a phonograph pick-up for modulating the frequency of an oscillator, in combination, a pair of cylindrical members of high permeability material, each of said members having an annular depression therein to form an outer shell and an inner pole piece, said pole pieces being shorter than said shells, coils in said annular depressions, means mounting said cylindrical members with the rims of the shells in abutting relationship forming a space between said pole pieces, a disk of high permeability material mounted in said space

between said pole pieces, and a lever carrying said disk, said lever terminating in a stylus at its opposite end whereby movement of said stylus in accordance with the grooves of a phonograph record or the like will move said high permeability disk into and out of a normal position in which its axis is more or less nearly coincidental with the axis of said pole pieces.

BRUCE ROBERTS.
